UNITED STATES PATENT OFFICE.

WILLIAM H. CLEVELAND, OF WELLINGTON, KANSAS.

RAIL-ANTICREEPER TIE-PLATE.

1,346,398.

Specification of Letters Patent. Patented July 13, 1920.

Application filed July 7, 1919. Serial No. 309,028.

To all whom it may concern:

Be it known that I, WILLIAM H. CLEVELAND, a citizen of the United States, residing at Wellington, in the county of Sumner and State of Kansas, have invented new and useful Improvements in Rail-Anticreeper Tie-Plates, of which the following is a specification.

My present invention pertains to railway track appliances and it contemplates the provision of an anti-rail creeper tie-plate whereby creeping or longitudinal movement of the rails in both opposing directions is effectually precluded.

The invention further contemplates the device of the character set forth that is easily adjusted and inexpensively produced and when applied in the proper manner will not only prevent the above-mentioned movement of the rails but will also assist in maintaining the gage of the rails at all times and protect the tie from mechanical rail wear.

With the foregoing in mind the invention will be fully understood from the following description and claims when the same are read in connection with the drawings, accompanying and forming part of this specification, in which:

Figure 1 is a top plan view showing my novel tie-plate as assembled with respect to a tie, and the rail thereof.

Fig. 2 is an end elevation showing the rail in its proper relative position with respect to the plate.

Fig. 3 is a perspective view illustrating the top member that goes to make up the plate and further illustrating the downwardly extending portion that grips the cross-tie on which the plate is mounted.

Fig. 4 is a perspective view of the bottom member that goes to make up the assembled plate.

Fig. 5 is an inverted perspective of the plate illustrated in Fig. 3, and,

Fig. 6 is a section taken through the central portion of the plate and showing the several elements as properly assembled, but eliminating the rail gripping means of the plates.

Similar numerals of reference designate corresponding parts in all of the views of the drawings.

For the sake of clearness and in order to enable others to readily appreciate the in-

vention, I have designated the member illustrated by Fig. 3 as the top member, and the member illustrated by Fig. 4 as the bottom member, and I would distinctly have it understood that because of their constructions either member may be employed on the right or left-hand side of a rail with equal facility. In other words, the device is what may be termed "fool proof."

My novel tie plate comprises the members 1 and 2 and each of said members is provided with a clamp jaw 3 at one end thereof that firmly grips or clamps the rail flange 4 (Fig. 2) and each of said members is provided with a longitudinally extending boss 5 that extends from the inner end of the jaw 3 to the full extent of the member except where it is broken by an elongated spike hole 6, which is of a peculiar construction for a purpose hereinafter set forth in detail.

Both of the members, which are in duplicate form are provided with channel grooves 7 and these grooves are formed transversely through the assembled plate in such manner at an angle of approximately 2° in every 8", so as to form a wedge shape section of each of the members 1 and 2. It will be appreciated by reference to Figs. 3 and 4 that one member is provided with a groove 7 in its underside and the opposite member is provided with the groove in its upper face.

As clearly appears in Figs. 5 and 4, it will be seen that in order to form the jump connection of the members under the rail, I cut away the gripping members as indicated by 8 and also to reduce the cost of manufacture and to overcome vibration due to contact between the rails and plates, I indent a portion of each member 1 and 2 as indicated by 9.

Because of their construction, the members 1 and 2 have a wedge-action with each other to grip the rail base.

As will be seen by reference to the drawings, each member 1 and 2 has a downwardly directed portion 10 and in practice when the assembled plate is properly positioned on a tie and the clamp jaws 3 grip the sides of the base of the rail; one of the abutting portions 10 would prevent movement of the member to which it is attached and the rail in creeping will carry the other member forward to cause a lateral gripping of the rail between the jaws 3, which action occurs from traffic in either direction,

and hence it will be appreciated that the portions 10 cause a wedging to take place between the jaws and rail.

The wedging inclination thus brought about will take place immediately on creeping of the rails but in order to be doubly assured that the members 1 and 2 will immediately stop movement toward each other and to further assist in maintaining the perfect gage of the tracks the downwardly extending lugs 10 will on movement of members 1 and 2 abut against their complementary tie and hence prevent the members 1 and 2 from wedging too strongly against the base of the rails. This is particularly desirous when for any reason occasion arises demanding the removal of the rails.

The spike slots by preference are of any shape or size and extend $\frac{1}{16}$ " under and across the base of the rails at an angle and it is my desire to use a spike $2\frac{1}{8}$ " long and $\frac{9}{16}$ " by $\frac{9}{16}$ " in diameter so that when the same is driven in the slot holes it will engage the base of the rail and force any chafing to take place between the spike and base. Manifestly the elongated slots will accommodate the spike during lateral movement of the members 1 and 2.

The space between the members 1 and 2 adjacent the grooves 7 permits the ready connection of the members by simply dropping the tongue and groove of one member into the complementary tongue and groove of the opposing member.

I would have it here understood that the flange 4 is engaged by the jaws 3 only to the extent of about two-thirds of an inch, which distance I consider sufficient to accomplish the purposes of my invention.

It will be gathered from the foregoing that the device is simple in construction and easy to produce and assemble and contains no delicate parts such as are likely to become useless after a short period of use. Moreover the device may be used in sufficient numbers to control either light or heavy traffic, and can further be employed in conjunction with any form of rail joint to protect the rail from injury due to creeping. The device may also be employed in sufficient numbers to eliminate the use of fish plates and other well known devices with which antirail creeping devices are used at present.

It may be well to state that the members 1 and 2 have the flange extending their full length along the rail flange except where broken to make room for the slot holes or spike holes.

Having described my invention, what I claim and desire to secure by Letters-Patent, is:

1. In a rail plate the combination of a member having one side edge cut at an angle, a flange extending approximately the full length of the member on the other side thereof, a rail gripping jaw at one end of the member, a slot hole at the opposite end from the jaw arranged in the member and cut at an angle to the flange, a downwardly extending tie engaging portion formed on one end of the member and a tongue and groove formed in the underside of the member and extending parallel with the angular side of the member, and an opposing member constructed similar to the first-named member, but having its tongue and groove arranged in its upper face, whereby the tongue and groove of the first-named member may interlock with those of the second member.

2. In a rail gripping means, the combination of a tie plate formed of two members each having a jaw arranged on one side thereof, a flange on said side, a downwardly extending tie engaging portion on the end of each member and a tongue and groove provided in each member that are engaged by the tongue and groove of the other member and so constructed and arranged that movement longitudinally of a rail that normally rests on the members, will cause wedging of the jaws of each member and the rail base.

3. In a rail plate, the combination of two plates each formed with one straight side, and an opposing side cut at an angle, whereby one end will be of larger size than the other, a depending tie engaging portion formed on the large end of each plate, a rail jaw mounted on the straight side of each plate, and a flange on said side of the plate, and a longitudinal tongue and groove that extends along the angular side of each member; one of said members being provided with the tongue and groove in its upper face, and the other of said members being provided with the tongue and groove in its lower face, substantially as and for the purpose set forth.

In testimony whereof I have hereunto set my hand in presence of two subscribing witnesses.

WILLIAM H. CLEVELAND.
